UNITED STATES PATENT OFFICE.

ERLO H. GRAY AND LEON C. GRAY, OF ROCHESTER, NEW YORK.

COPY-HOLDER.

1,201,574.

Specification of Letters Patent. Patented Oct. 17, 1916.

Application filed July 20, 1912. Serial No. 710,631.

To all whom it may concern:

Be it known that we, ERLO H. GRAY and LEON C. GRAY, citizens of the United States, residing at Rochester, in the county of Monroe and State of New York, have invented certain new and useful Improvements in Copy-Holders, of which the following is a specification.

The object of our invention is to provide an improved device for holding copy from which a stenographer or clerk may be transcribing.

Another object of our invention is to provide mechanism by which said plate may be advanced progressively step by step.

Another object of our invention is to provide an improved clutch mechanism by which said advancement may be secured.

These and other objects of our invention will be fully illustrated in the drawings, described in the specification and pointed out in the claims at the end thereof.

In the accompanying drawings, Figure 1 is a perspective view of our improved copy holder with the attachments therefor, mounted on a suitable base. Fig. 2 is a detail perspective view of the copy holder with the platen removed. Fig. 3 is a detail perspective view of the base viewed from the rear. Fig. 4 is a view of the same parts shown in Fig. 3, the parts being shown in a different position. Fig. 5 is a detail view of the upright support for the platen. Fig. 6 is a section on the line 6^x—6^x in Fig. 5. Fig. 7 is a detail perspective view of one of the joints between the platen and the upright, the parts being separated. Fig. 8 is the same as Fig. 7, with the parts brought together. Fig. 9 is a detail view of the bracket for supporting the line indicator. Fig. 10 is a detail view of one of the fingers for holding the paper in position. Fig. 11 is a detail view of a portion of the upright, showing the clutch between the stationary

and moving part of the upright, the traveler and the link being omitted. Fig. 12 is a perspective view of the link. Fig. 13 is a perspective view of the traveler. Fig. 14 is a vertical section on the line 14^x—14^x in Fig. 11, the link and traveler being shown in place and the clutches engaged. Fig. 15 shows the parts of Fig. 14 in a different position, with the clutches disengaged. Fig. 16 is a rear view of the upper right hand

corner of the platen. Fig. 17 is a section on 55 the line 17^x—17^x of Fig. 2. Fig. 18 is a section on the line 18^x—18^x of Fig. 1.

In the accompanying drawings like reference numerals refer to like parts.

In the drawings reference numeral 1 indicates a base on which the copy holder is mounted and on which the typewriter may also be fastened. This base may be the top of a desk or it may be a board placed on top of the bed of the desk for a purpose that 60 will presently be described.

Fastened to the base 1 is the pedestal 2, upon which the parts are supported. Pivotally mounted upon the pedestal 2 is the upright 3 which comprises a bracket 4 having a depending lug 5 with a pin 6 thereon which engages suitable openings in the lugs 7 and 8 of the pedestal 2.

Mounted on the pedestal 2 is the upright catch 9. Mounted on the bracket 4 is the screw 10 having a helical compression spring 11 surrounding it. This screw 10 passes through a clip 12 which is yieldingly pressed down upon the base of the bracket 4 by the spring 11. The upright 3 may be placed in 70 a horizontal position, as is shown in Fig. 4, and may be raised to a vertical position as shown in Fig. 3, in which position it will lock by the engagement between the clip 12 and the upright 9.

Mounted in the pedestal 2 in the lugs 13 and 14 is the lever 15. Mounted in the pedestal 2 in the lug 16 is the rock shaft 17, on the end of which is fastened the crank 18, as shown in Figs. 3 and 4, which crank has a pin 19 thereon, which pin engages with a slot 20 in the lever 15, by which the lever may be rocked by the rocking of the shaft 17. The front end of the shaft 17 is journaled in the lug 21. The front end of the shaft 17 ends in an arm or crank 22 having a knob 23 on the end thereof by which it may be conveniently operated.

Mounted in the base 24 of the lug 21 is the screw 25 which may be adjusted to limit 100 the angular movement of the arm 22, for a purpose that will presently be described. On the bracket 4 is mounted the upright 3, which upright is channel shaped as is shown in Figs. 11 and 17. Mounted on this channel 105 is the bracket 26 on which is carried a pin 27, on which the line indicator 28 is rotatably mounted by means of the sleeve 29,

the sleeve being clamped in place by means of a binding screw 30. The bracket 26 carries a socket 31 in which may be supported a standard for a lamp.

5 Mounted on the bracket 4 and fastened to the channel 3 is the cylinder 32, which cylinder is shown in vertical section in Fig. 6 and in horizontal section in Fig. 17.

10 Mounted to slide in the channel 3 is the traveler 33, which traveler has the bracket 34 fastened at the top thereof from which is supported the piston 35, which piston works in the cylinder 32 for the purpose of forming a pneumatic chuck for the traveler when 15 it is permitted to fall. The piston 32 is provided with a washer 36 on the bottom thereof, by which the air is compressed in the cylinder. The cylinder is perforated at 37, 38 and 39 for the purpose of permitting 20 the escape of air from the cylinder as the piston descends, the openings 37, 38 and 39 being small enough to retard the escape of the air so as to compel the piston and the traveler to descend slowly. The bottom of 25 the cylinder 32 below the opening 39 forms an air tight pocket which cushions the piston in its descent and brings it slowly to rest.

The traveler is raised through successive steps and held at the end of each step by 30 mechanism which we will now describe. Mounted to reciprocate in the upright 3 is the link 40, which link at the bottom is turned out and is connected to the lever 15. This link passes through the lug 41 which is 35 struck out from the upright 3 and is perforated to receive it. At the top the link has fastened thereto the moving cam plate 42. This cam plate is upturned at the bottom at 43 to afford a convenient place of 40 attachment for the link 40. At the top it has the inclined cam surfaces 44 and 45 bent up thereon. At the top two blisters 46 and 47 are bent into the plate, by which the wire spring 48 is held in place. In the face 45 of the cam the lug 49 is struck up and bent in. Mounted on the upright is the stationary cam plate 50. This cam plate has the two lugs 51 and 52 bent over on the top thereof, which lugs serve as supports for the 50 rollers 53 and 54, these lugs serving to limit the downward movement of the rollers. Also struck up on the cam plate are the inclined cam surfaces 55 and 56. Pivots mounted on the stationary cam plate 50 are 55 the levers 57 and 58. These levers have the out turned ends 59 and 60 at the inner ends and have the out turned ends 61 and 62 at the outer ends. The outer ends 59 and 60 have their broad surfaces presented vertically and the ends 61 and 62 have their broad surfaces extended horizontally. Above the out turned ends 61 and 62 and between the cam surfaces 55 and 56 and the upright 3, are placed the rollers 63 and 64. 60 Near the top of the cam plate 50 is mounted

the stud 65 on which is mounted the wire spring 66. The ends of this spring bear on the rollers 63 and 64 and by this spring the rollers are yieldingly held in place against the cams 55 and 56, being supported in such 70 position by the out turned ends 61 and 62 when the traveler 33 is removed. The rollers 53, 54, 63 and 64 each have an annular groove therein to receive the springs 48 and 66 respectively so as to maintain positive 75 engagement therewith.

The traveler 33 is a sheet of metal bent to the form of a channel as shown in cross section in Fig. 17 and in perspective in Fig. 13. The traveler has the lugs 67 and 68 struck up thereon for the purpose of supporting the platen thereby. The sides of the traveler 33 pass between the sides of the channel 3 and the rollers 53 and 63 on one side and the rollers 54 and 64 on the other 80 side. These rollers are normally pressed out against the sides of the channel 33, or in other words, they are normally pinched between the sides of the channel and the inclined cam surfaces 44 and 55 on one side 85 and 45 and 56 on the other side, as clearly appears in Fig. 14.

As above explained, the cams 44 and 45 are on the moving cam plate 42 and the cams 55 and 56 are on the stationary cam plate 50. 90 These various parts form a clutch between the moving cam plate 42 and the traveler 33, which clutch operates as follows: When the button 23 is depressed the lever 15 is rocked down at the pin 19 and is raised at the opposite end, carrying up therewith the link 40 and the cam plate 42. This cam plate pinches the rollers 53 and 54 against the traveler 33 by means of the cams 44 and 45, and carries the traveler up therewith. The 100 traveler as it rises passes by the rollers 63 and 64 which are held down by the spring 66, and as soon as the button 23 is released the moving cam plate 42 drops and the rollers 63 and 64 form a clutch that binds 105 the moving traveler 33 in its raised position and holds it there. The moving cam plate 42 drops with the rollers 53 and 54 to take a fresh engagement with the traveler so that the operation of lifting it can be repeated. 110 In this way the traveler is advanced step by step from the lowest position to the highest position in the limits of its travel. 115

It is necessary to reset the traveler from any position to which it may have been elevated, and this resetting of the traveler we 120 secure as follows: The lug 49 on the moving cam plate 42 normally rests above and out of engagement with the out turned ends 59 and 60. When the button 23 is raised it operates 125 through the train of mechanism to pull down on the link 40 and the cam plate 42. The lug 49 then engages with the out turned ends 59 and 60 and draws the levers down at their inner ends, causing them to raise at 130

their outer ends, and with them the rollers 63 and 64 are raised, so that they no longer pinch between the cam surfaces 55 and 56 and the sides of the traveler 33. At the 5 same time as the cam plate 42 is drawn down, the cams 44 and 45 move away from the rollers 53 and 54 which are held against following them by reason of the out turned ends 51 and 52 on the stationary plate 50. 10 This then releases the traveler 33 from the clutch and it is then free to drop by gravity, the rollers being held in their upper position in the meantime by the out turned ends 51, 52, 61 and 62. 15 The position which the parts occupy when the traveler is at rest clutched in elevated position is shown in Fig. 14. The position which the parts occupy when the clutch is released to permit the dropping of the traveler is shown in Fig. 15. The maximum 20 length of each upward step of the traveler is determined as follows: The downward movement of the arm 22 is limited by the set screw 25. The upward movement of it 25 is limited by the moving cam plate 42 which carries the spring 48, which in turn makes contact with the rollers 53 and 54, which rollers are held against downward movement by the out turned supporting plates 30 51 and 52, which in turn are part of the stationary cam plate that is rigidly supported on the upright 3. The moving cam plate 42 is thus suspended from the rollers 53, being free to move up therefrom but being 35 restrained in its downward movement by means of the spring 48. This suspension of the moving cam plate 42 determines the proper position of the button 23 on the arm 22 and the arm 22 and button 23 can be 40 raised above their normal position by drawing down on the link 40 and moving cam plate 42, which in turn flexes the spring 48 as shown in dotted lines in Fig. 15. The spring 48 then fixes the normal upper position of the button 23 and the set screw 25 45 limits the downward movement thereof, and the contact between the lug 49 and the out turned ends 59 and 60, together with the flexing of the spring 48 limits the extreme 50 downward movement of the cam plate 42 and the extreme upward movement of the button 23. Quick downward movement of the moving cam plate 42 is secured by the spring 69 which is secured to the link 55 40 at one end and to the upright 3 at the other end. See Fig. 5. The tension of this spring in its normal position is not sufficient however to flex the spring 48 or disturb the position of the cam plate 42. The relation 60 of the parts is such that the upward travel of the link 40 is about seven-tenths of an inch and the platen is advanced through steps of about six-tenths of an inch. Supported on the traveler 33 is the platen 70. Struck 65 up on the traveler are the lugs 67 and 68.

Fastened on the back of the platen are two sockets, one of which is shown at 71, which sockets engage respectively with the lugs 67 and 68. The socket is extended downwardly on one side at 72, which extended side serves as a guide against the lugs 67 and 68 when steering the platen 70 to place in engagement therewith.

In Fig. 7 we have shown the platen being placed in position with the lug 67 against the guide 72, and in Fig. 8 we have shown the platen in its final position with the lug 67 in engagement with the socket 71. The top of the socket is closed with the lip 72, the extended end of which is fastened to the platen. At the side of the socket 71 is the extension 73 against which the platen bears for the purpose of giving a firm, positive bearing between the platen and the traveler to prevent the platen from swinging on the traveler. The socket 71 and extension 73 may be fastened on the platen in any desired manner. At the top of the platen we provide the spring pressed wire loops 74 and 75, which wire loops are normally pressed against the front of the platen by the torsion springs 76 and 77. The wire loops 74 and 75 carry thereon the rubber washers 78, 79, 80 and 81 which bear against the paper or note book that may be placed upon the platen. At the top of the platen we provide, pivotally mounted on the margin thereof, a spring pressed finger 82 having the handle or finger piece 83 thereon. The platen is wound around its margin by the wire 84, on which wire the finger piece 83 is pivotally mounted. Coiled around this wire 84 is the torsion spring 85, one end of which is fastened to the platen and the other end of which bears against the finger piece 83 by which the pointer 82 is normally held in engagement with the platen.

As shown at the top in Fig. 1, the wire 82 is curved away from the platen at the middle and terminates at its outer end in a loop. Near the bottom of the platen is mounted in the same way a spring pressed finger piece 86 having a pointer 87 thereon, which pointer is preferably straight. The pointers 82 and 87 serve merely as retaining rods to hold the paper in position. The line indicating is preferably done by the pointer 28 which is mounted on the upright 3 and does not travel with the platen. Mounted on the rear of the platen 70 are the two rollers 88 and 89. On the roller 89 is mounted a roll of paper 90, the web of which 91 is intended to pass over the front of the platen to the other roller. The roller 88 has a beveled gear 92 at the top. Mounted on the platen 70 is a shaft 93, on the inner end of which is a beveled pinion 94 adapted to mesh with the beveled gear 92, and on the outer end of which is mounted a thumb wheel 95 by which the shaft 88

may be rotated and the paper web 91 drawn to the roller 88 from the roller 89. The platen so equipped may be removed from the traveler and used as a lapboard and 5 copy book combined, the paper exposed on the platen being filled with the stenographer's notes or other writing, and the paper then reeled from one roll to the other, exposing a fresh surface as the notes are 10 placed thereon. The paper may then be rewound so as to expose the notes at the beginning, and the platen may be placed upon the traveler, after which the transcribing of the notes upon the typewriter 15 can be begun, the paper being wound forward again as the notes are copied.

A great many typewriters are equipped with roll top desks, so called, and on account of this and for other reasons it is desirable to have the copy holder so arranged 20 that it can be stored away with the typewriter in connection with which it is used in a comparatively small space. It is also desirable to have the copy holder so arranged 25 that it occupies a comparatively small space in transportation and so that it is easily set up when it is placed in position. For this reason we have arranged the copy holder so that it can be folded up into 30 a comparatively small space, and the special features of the copy holder by which this arrangement is secured we will now describe.

As above described, the upright 3 is pivotally mounted between the lugs 7 and 8 on the pedestal 2 and is held in an upright position by the engagement between the clip 12 and the upright 9. The platen 70 may be removed from the upright and the upright 40 may be turned down to the horizontal position as indicated in Fig. 4, and in so doing it is not necessary to reach any part behind the typewriter, all the parts which are essential for this operation being exposed above 45 the typewriter. To facilitate storing away these parts and making them more compact, the bracket 26 is jointed. The bracket 26 includes the part 97 which is rigid with the upright 3 and in which is mounted the binding screw 98 on which is pivotally mounted 50 the main part of the bracket 26.

As shown in Fig. 9, the parts are coupled together by the plate 99 which is integral with the main part of the bracket and which 55 has a slot 100 by which it engages the binding screw 98. A washer or bushing 101 is interposed between the knurled head of the screw 98 and the plate 99. The part 97 and the main part of the bracket 26 have square 60 abutting ends, each of which forms a shoulder for the other and by which the bracket is held firmly in its extended position when the screw 98 is clamped in position.

In using this copy holder in connection 65 with some roll top desks it has been found

that there is not room enough back of the machine and under the roll top of the desk for the platen and copy holder. For this reason the machine must be set out on the bed of the desk far enough to permit the 70 copy holder with its platen to be set in behind it so as to project up in front of the roll top. The machine however in this position would ordinarily interfere with the closing of the desk. Instead therefore of 75 setting the copy holder and the machine directly upon the bed of the desk we have found it desirable to set both the copy holder and the machine upon a board or plate which is then set on the bed of the desk, the 80 board or plate being moved out when the machine and copy holder are in use and being pushed back when it is desirable to close the desk. Such a board is shown in Fig. 1 and has a positive sliding engagement with 85 the bed of the desk and is prevented from sliding back by means of the hooks 102 shown at the front end of the board in Fig. 1, which hooks engage with the front end of the bed of the desk when the desk has 90 been closed up.

Having thus described our invention, what we claim as new and patentable is as follows:

1. In a copy holder the combination of an 95 upright support, a moving cam plate mounted thereon, rollers adapted to coöperate with said moving cam plate, stationary lugs on said support engaging with said rollers and preventing them from passing 100 therebelow, said moving cam plate being capable of movement downward out of engagement with said lugs, a spring attached to said moving cam plate, the arms of which engage with said rollers, by which said moving cam plate is yieldingly supported. 105

2. In a copy holder the combination of an upright support, a stationary cam plate mounted thereon, cams on said stationary cam plate and rollers positioned adjacent 110 thereto, levers pivoted on said plate having lugs on the outer ends thereof by which the rollers can be engaged and forced upward, lugs on the inner ends of said levers, a moving plate having a lug thereon capable 115 of engaging with the lugs on the inner ends of said levers, by the movement of which said levers may be simultaneously rocked to engage with and lift the rollers.

3. In a copy holder the combination of an 120 upright support, a stationary cam plate mounted thereon, cams on said stationary cam plate and rollers positioned adjacent thereto, levers pivoted on said plate having lugs on the outer ends thereof by which the 125 rollers can be engaged and forced upward, lugs on the inner ends of said levers, a moving plate having a lug thereon capable of engaging with the lugs on the inner ends of said levers, by the movement of which 130

said levers may be simultaneously rocked to engage with and lift the rollers, a spring bearing on said rollers adapted to hold said rollers and levers down at the outer ends in 5 normal position.

4. In a copyholder the combination of an upright channel shaped support, a stationary cam plate and a moving cam plate in said support, a channel shaped traveler 10 mounted to slide in said support, the open side of said traveler facing the closed back of said support, cylindrical rollers interposed between said moving cam plate and said stationary cam plate and said traveler.

15 5. In a copyholder the combination of an upright channel shaped support, a stationary cam plate and a moving cam plate in said support, a channel shaped traveler mounted to slide in said support, the open side of 20 said traveler facing the closed back of said support, cylindrical rollers interposed between said moving cam plate and said stationary cam plate and said traveler, said cam plate consisting of a flat plate having 25 a flange bent up on one end thereof and two oppositely disposed cams formed on the other end thereof.

6. In a copyholder the combination of an upright channel shaped support, a channel 30 shaped traveler mounted to slide in said support, a cam plate moving in said support, said plate having two oppositely disposed cams formed on the sides thereof, a cylindrical roller placed between each of said 35 cams and said traveler, said parts forming

a clutch by which the traveler will be raised on the raising of the cam plate.

7. In a copyholder the combination of an upright channel shaped support, a channel shaped traveler mounted to slide in said support, a cam plate moving in said support, said plate having two oppositely disposed cams formed on the sides thereof, a cylindrical roller placed between each of said cams and said traveler, said parts forming 40 a clutch by which the traveler will be raised on the raising of the cam plate, a second roller clutch interposed between said traveler and said support by which said traveler is supported in its raised position. 45

8. In a copyholder the combination of an upright support, cam plates rigidly fastened thereon, a traveler mounted to slide in said support between the sides of said upright and said stationary cams, a link having 50 55 cams at the top thereof mounted to reciprocate in said traveler, rollers interposed between said moving cams on said link and said traveler and rollers interposed between said stationary cams on said upright and said traveler, means for alternately clamping and releasing all of said rollers between said cams and said traveler.

In testimony whereof we affix our signatures in presence of two witnesses.
